UNITED STATES PATENT OFFICE.

GEORGE R. FARRELL, OF LEOMINSTER, MASSACHUSETTS.

DESIGN FOR A BANDEAU.

41,486.

Specification for Design. Patented June 20, 1911.

Application filed April 14, 1911. Serial No. 621,160. Term of patent 3½ years.

To all whom it may concern:

Be it known that I, GEORGE R. FARRELL, a citizen of the United States, residing at Leominster, in the county of Worcester and State of Massachusetts, have invented a new, original, and ornamental Design for a Bandeau, of which the following is a specification, reference being had to the accompanying drawing, forming part thereof.

The figure is a front elevation of a bandeau spread out flat showing my new design.

I claim:

The ornamental design for a bandeau as shown.

GEORGE R. FARRELL.
